US00D889501S

(12) **United States Design Patent** (10) Patent No.: **US D889,501 S**
(45) Date of Patent: ** Jul. 7, 2020

(54) **DISPLAY SCREEN WITH GRAPHICAL USER INTERFACE**

(71) Applicant: **Google LLC**, Mountain View, CA (US)

(72) Inventors: **Kunal Patel**, San Francisco, CA (US); **Brendan Pascoe**, San Francisco, CA (US); **David Chiu**, Oakland, CA (US); **Rachel Been**, San Francisco, CA (US); **Sameer Bansal**, San Francisco, CA (US); **Ke Li**, New York, NY (US); **Damien Correll**, Brooklyn, NY (US); **Philippe Cao**, Brooklyn, NY (US)

(73) Assignee: **Google LLC**, Mountain View, CA (US)

(**) Term: **15 Years**

(21) Appl. No.: **29/645,448**

(22) Filed: **Apr. 26, 2018**

(51) LOC (12) Cl. **14-04**

(52) U.S. Cl.

USPC **D14/487**

(58) **Field of Classification Search**

(57)

CLAIM

The ornamental design for a display screen with graphical user interface, as shown and described.

DESCRIPTION

The sole FIGURE is a front view of a display screen with graphical user interface, showing the new design.

The uneven-length broken line showing a display screen defines the boundary of the design and forms no part of the claim. The even-length dashed lines illustrate portions of the graphical user interface that form no part of the claimed design.

1 Claim, 1 Drawing Sheet
